Inventor:

Octavia Frasher:

By Henry L. Ernst Rely.

UNITED STATES PATENT OFFICE.

OCTAVIA FRASHER, OF PITTSBURG, PENNSYLVANIA.

DESIGN FOR A TORCH ATTACHMENT.

SPECIFICATION forming part of Design No. 26,200, dated October 20, 1896.

Application filed August 3, 1896. Serial No. 601,562. Term of patent 7 years.

To all whom it may concern:

Be it known that I, OCTAVIA FRASHER, a citizen of the United States of America, residing at Pittsburg, in the county of Allegheny and State of Pennsylvania, have invented a certain new and original Design for Torch Attachments, of which the following is a specification, reference being had therein to the accompanying drawing.

10 This invention relates to a certain new and original design for torch attachments, or may be referred to more particularly as a frame for carrying a shield or other device.

15 In describing the invention in detail reference is had to the accompanying drawing, forming a part of this specification, wherein like letters of reference indicate similar parts throughout the view, in which the figure is a perspective view of my design.

The leading features of my design consist 20 in the loop *a*, the upwardly-extending arms *b b*, transverse arms *c*, and horizontal arm *d*. A twisted arm *e*, attached to the loop *a*, carries an oblong weight *f*, and the arms *b b* are provided at their upper ends with projecting 25 points *g g* and at their base with similar projecting points *h h*.

What I claim is—

The design for a torch attachment, or frame, substantially as herein shown and described. 30

In testimony whereof I affix my signature in presence of two witnesses.

OCTAVIA FRASHER.
